UNITED STATES PATENT OFFICE.

CONRAD N. PETERSON, OF CAMP KEARNEY, CALIFORNIA.

CONTAINER-CAP MEANS.

Application filed May 26, 1924. Serial No. 715,934.

My invention relates to devices adapted to form closures for metal cases or the like and has for its objects: first, to provide a removable cover for metal cans, tubes or the like, which is adapted to form a hinged closure for said metal cans, tubes or other devices, and to provide means for releasing said hinged closure from the proximity of the opening of said metal cans, tubes or devices.

I attain these objects by the construction illustrated in the accompanying drawing in which Fig. 1 shows a plan view of a receptacle provided with a cover comprising my invention. Fig. 2 shows a side elevation of said receptacle with a removable cover shown in section to more clearly show its general arrangement and construction. Figure 3 shows a section on line 3—3 of Fig. 2. Fig. 4 shows a section on line 4—4 of Fig. 2.

A receptacle 1, a cover 2, and a hinge bar 3, form the principal parts of this device.

In the device as illustrated on the drawing and more particularly referring to Fig. 2, a metal receptacle 1 is provided with a throatlike extension 1^a, having formed near its extremity an outwardly projecting ridge 1^b and a tapered end 1^c, over which a cover 2 is adapted to be seated and held in place by the hinge bar 3 and by the clasp 2^a. The cover 2 is provided with a hinge lip 2^b adapted to swivel on the hinge pin 2^c and between the forked ends 3^a of the hinge bar 3.

The hinge bar 3 is pivotally hinged to the throat extension 1^a of the receptacle 1 by a lug 1^d entering holes 3^b provided in said hinge bar 3.

A mole or protuberance 1^e is formed at each side of the throat extension 1^a of the receptacle 1 near the upper end of said throat extension 1^a, for the purpose of providing a resistance against the free swinging of the hinge bar 3 on the pivot lugs 1^d. The upper end of the hinge bar 3 surmounts the upper end of one half of the throat extension 1^a, and the forked ends 3^a are formed on the upper edge thereof, while the lower prongs 3^c of said hinge bar 3 extend down either side of the throat extension 1^a.

A mound 3^d formed on the hinge bar 3 is adapted to form a seat over the mole 1^e, thus securing the hinge bar 3 in proper relation to the throat extension 1^a of the receptacle 1, when it is desired to leave the cover 2 closed or when same is to be opened

on the hinge pin 2^c. As in many cases it is desired to entirely free the throat extension 1^a of the cover 2, a slight pressure in a downward direction on the cover 2 when same has been swinging away from the throat extension 1^a, as shown in the upper dotted position thereof, will swing the hinge bar 3 with the cover into the lower dotted position thus clearing the throat extension 1^a entirely from any incumbrance.

Having thus described my invention what I claim as new and desire to protect by Letters Patent, is:

1. In a container cover means, a receptacle having a throat-like extension provided with a ridge and an inwardly tapered end formed on the upper end of the said throat-like extension, a bar pivotally mounted near the lower end of the said throat-like extension and a considerable distance from and below said ridge and a cover hinged on said bar adapted to fit on said ridge and inwardly tapered end.

2. In a container cover means, a receptacle having a reduced, straight, throat-like extension and provided with a ridge and an inwardly tapered end formed on the upper end of the said throat-like extension, a bar pivotally mounted at its opposite ends near the lower end of the said throat-like extension and a cover hinged on said bar at its middle portion intermediate its ends and adapted to fit on said ridge and inwardly tapered end.

3. In a container cover means, a receptacle having an opening, a cover supporting bar means pivotally mounted at the opposite outer sides of the receptacle and shiftable, when covering the opening of the receptacle, with one end adjacent the opening, and a cover pivotally mounted on said bar means adapted to cover said opening, said bar means being also shiftable with said cover a considerable distance from said opening.

4. In a container cover means, a receptacle having an opening, a cover supporting bar pivotally mounted at the outer side of the receptacle and shiftable with one end adjacent the opening, means in connection with the receptacle and said bar for detachably holding the latter with its one end adjacent said opening, and a cover pivotally mounted on said bar adapted to cover said opening.

5. In a container cover means, a receptacle having an opening, a cover supporting bar pivotally mounted at the outer side of the re-

ceptacle and shiftable with one end adjacent the opening, means in connection with the receptacle and said bar for detachably holding the latter with its one end adjacent 5 said opening, a cover pivotally mounted on said bar adapted to cover said opening, and means on said cover for fastening the same in a closed position over said opening.

6. In a container cover means, a receptacle 10 having a reduced throat open at its end, a substantially U-shaped bar pivotally mounted at the ends of its legs to and at the opposite outer sides of the throat and

adapted to extend with its cross portion adjacent the open end of said throat, said bar 15 being adapted to be folded downwardly with its cross portion free and clear of said throat, and a cover pivotally mounted at one side to the cross portion of said bar and adapted to cover said opening when the cross portion 20 of said bar is positioned adjacent said opening.

In testimony whereof, I have hereunto set my hand at San Diego, California, this 17th day of May, 1924.

CONRAD N. PETERSON.
